DELIVERY CONTROL MECHANISM FOR CONVEYERS

Harry J. Ferguson, Elkins Park, Pa., assignor to
 Harry J. Ferguson Co., Jenkintown, Pa., a corporation of Pennsylvania

Application April 11, 1951, Serial No. 220,405

6 Claims. (Cl. 193—35)

1

This invention relates to delivery control mechanism for conveyors and more particularly to apparatus for controlling the delivery of packages or commodities from a branch conveyor to a main conveyor or from two meeting conveyors.

It is the principal object of the present invention to provide delivery control mechanism for conveyors having a meeting branch, or two meeting sections, in which the arrival of a package at a predetermined location on one portion of the conveyor will operate the mechanism and permit the passage of the article while preventing the delivery of a subsequently arriving package on another portion of the conveyor.

It is a further object of the invention to provide apparatus of the character aforesaid which is simple and reliable in its construction, which does not require any external source of energy, and which may be quickly and easily installed in existing conveyor installations.

It is a further object of the present invention to provide control mechanism of the character aforesaid in which the arrival of a package on one branch of meeting branches of a conveyor is delivered without interruption while a subsequently arriving package or packages are held against delivery at the meeting branch for a sufficient time interval to prevent collision of the packages.

Other objects and advantageous features of the invention will be apparent from the specification and claims.

The nature and characteristic features of the invention will be more readily understood from the following description, taken in connection with the accompanying drawings forming part hereof, in which:

Figure 1 is a top plan view of a fragmentary portion of a conveyor with a meeting branch having the control mechanism in accordance with the invention applied thereon;

Fig. 2 is a fragmentary top plan view, enlarged, of a portion of the control mechanism shown in Fig. 1;

Fig. 3 is a vertical sectional view taken approximately on line 3—3 of Fig. 2;

Fig. 4 is a side elevational view of the structure shown in Fig. 2 with the gate removed therefrom;

Fig. 5 is a horizontal sectional view taken approximately on the line 5—5 of Fig. 3 and showing one condition of the operation; and

Fig. 6 is a view similar to Fig. 5 taken approximately on line 6—6 of Fig. 3.

Referring now more particularly to the draw-

ings, in which a preferred embodiment of the invention is illustrated, a conveyor 10 is shown which may be of any desired type, a gravity roller type being shown merely by way of example. A branch conveyor type of similar character is shown as disposed in meeting relation to the conveyor 10.

The control mechanism in accordance with the present invention and shown generally at 12 is preferably located in the angle between the conveyor sections 10 and 11.

The control mechanism 12 preferably includes a supporting stand or frame 13 mounted in any desired manner and preferably rigidly fixed at the desired location with respect to the conveyor 10 and the branch conveyor 11. The stand 13 is preferably provided with a split clamping sleeve 14, with tightening bolts 15 for supporting an upright post 16. The lower end of the post 16 may be supported in rubber bushings 17 clamped in the sleeve 14, and the post 16 may be elevated to the desired extent to accommodate it to the level of the conveyors 10 and 11.

The post 16 has an upper fixed shaft portion 19 on which the controlling mechanism, hereinafter more fully explained, is supported.

The post shaft portion 19 preferably has adjustably secured thereto a bracket 20 with a central sleeve 21, secured to the shaft portion 19 by a set screw 22. The sleeve 21 has upper and lower bearing surfaces 23 and 24. The bracket 20 also has a bracket arm 25 extending outwardly from the sleeve 21, and, at the outer end thereof, a pin socket 26, is provided.

The bracket 20 also has at the portion thereof opposite the bracket arm 25, an upper spring abutment bracket 26 and a lower spring abutment bracket 27 within which spring pins 28 and 29 are mounted, having heads 30 and 31 with springs 32 and 33 interposed between the heads 30 and 31 and the abutment brackets 26 and 27.

An arcuate locking lever 35 is provided having a pivot pin 36 mounted therein for movement in the pin socket 26. The locking lever 35 has arms 38 and 39, on the outer ends of which cam follower rollers 40 and 41 are rotatably mounted on studs 42 and 43.

An upper movable sleeve 46 is provided, on the shaft portion 19 and above the bracket 20, needle bearing rollers 47 being interposed between the sleeve 46 and the shaft portion 19. The needle bearing rollers 47, at their lower ends bear on the upper bearing surface 23 of the fixed sleeve 21, and at their upper ends bear on a collar 48 which may be secured to the shaft portion 19 in any de-

sired manner, such as by a set screw 49. The sleeve 46 has an outwardly extending flange 50, at one side of which a downwardly extending cam block 51 is mounted by studs 52. The cam block 51 has vertically disposed an end locking face 53, a curved edge 54, and an outer flaring face 55. At the end of the cam block 51, opposite the end face 53, a notch 56 is provided, within which the head 30 of the spring pin 28 engages.

The flange 50, at the opposite side thereof from the cam block 51, has a gate supporting bracket 57 secured thereto by studs 58, at any desired angular position, and, from the bracket 57, an actuating and locking gate 60 extends outwardly over the conveyor section 10.

A lower movable sleeve 71 is provided, on the shaft portion 19 and below the bracket 20, needle bearing rollers 72 being interposed between the sleeve 71 and the shaft portion 19. The needle bearing rollers 72 at their upper ends bear on the lever bearing surface 24 of the fixed sleeve 21, and at their lower ends bear on a collar 73 which may be secured to the shaft portion 19 in any desired manner, such as by a set screw 74. The sleeve 71 has an outwardly extending flange 75, at one side of which an upwardly extending cam block 76 is mounted by studs 77. The cam block 76 has vertically disposed an end locking face 78, a curved edge 79, and an outer flaring face 80. At the end of the cam block 76, opposite the end face 78, a notch 81 is provided, within which the head 31 of the spring pin 29 engages.

The flange 75, at the opposite side thereof from the cam block 76, has a gate supporting bracket 82, secured thereto by studs 83, at any desired angular position, and, from the bracket 82, an actuating and locking gate 84 extends outwardly over the conveyor section 11.

The relative positioning of the supporting bracket 57 of the gate 60 with respect to the cam block 51 on the flange 50 and of the supporting bracket 82 of the gate 84 with respect to cam block 76 on the flange 75 permits of a range of angular adjustment to accommodate the different meeting angles of conveyors which are encountered.

The sleeve 21 is preferably provided with a stop 88 for limiting the extent of movement of the cam blocks 51 and 76.

The mode of operation will now be pointed out. With no packages on the conveyors 10 and 11, the gates 60 and 84 will be at equilibrium locations shown in Figs. 1 and 2 and the arcuate locking lever 35 will be in a neutral position, as shown in Fig. 2, with the roller 40 in engagement with the edge 54 and with the roller 41 in engagement with the edge 79. Upon the arrival of a package either on the conveyor 10 or on the conveyor 11, this equilibrium position will no longer be maintained.

For purposes of explanation it may be assumed that packages advance along the conveyors 10 and 11 towards their junction, and that prior to the arrival of a package at the gate 84 a package arrives at the gate 60, strikes the gate 60, and moves the gate 60 counter-clockwise, as shown in Figs. 1 and 2, to a position to permit the package to move past the gate 60.

As soon as a force, such as that applied by an advancing package, is effective on the gate 60 and 70 moves it to pass, this tends to move the upper sleeve 46 and the cam block 51 carried thereby in a counter-clockwise direction.

Upon movement of the cam block 51, the edge 54 presses on the roller 40 and causes the roller 75

40 and its arm 38 to move outwardly. Further turning movement of the sleeve 46 advances successive portions of side face 55 of cam block 51 against the roller 40.

5 The swinging movement thus imparted to the lever 35 simultaneously moves the roller 41 inwardly along the end face 78 of the cam block 76. The engagement of the roller 41 with end face 78 locks and holds the cam block 76 and its sleeve 71 against movement, so that the gate 84 is locked and held against movement.

15 Any package advancing to the gate 84, while it is in this locked condition is held until the gate 60 returns to its initial position and permits the lever 35 to again assume its neutral position as referred to above.

20 Upon movement of the cam block 55 by the gate 60 the notch 56 engages the head 30 and the spring 32 is compressed to provide a restoring force which is effective when the package passes the gate 60 and permits its return to its initial position.

25 If a package arrives at the gate 84 prior to the arrival of a package at the gate 60, the gate 84 is moved clockwise, as shown in Figs. 1 and 2 to permit the package to pass that gate. As the gate 84 moves in this manner the lower sleeve 71 and the cam block 76 carried thereby are moved. The edge 79 of the cam block 76 moves the roller 41 and the arm 38 outwardly and further turning movement of the sleeve 71 advances successive portions of the side face 80 against the roller 41.

30 The swinging movement thus imparted to the lever 35 moves the roller 40 inwardly along the end face 53 of the cam block 51, thus locking and holding the cam block 51, the sleeve 46 and the gate 60 against movement.

35 The spring 33 is effective, upon the release of the gate 84 by the passing package, to provide a restoring force for returning the gate 84 to its initial position.

I claim:

1. In control mechanism, a vertical support, 45 a movable member pivotally mounted on said support and adapted to extend outwardly in a predetermined position, a cam member supported by said movable member and having a locking end face and a vertical control face, a second movable member pivotally mounted on said support and adapted to extend outwardly in a predetermined position, a second cam member supported by said second movable member and having a locking end face and a vertical control face, a shiftable control member having spaced followers for engagement with the faces of said cam members, said control member upon movement of one movable member from its predetermined position having one follower positioned by the vertical face of one cam member to dispose the other follower in engagement with the locking end face of the other cam member and thereby hold said other movable member against movement from its predetermined position.

2. Control mechanism as defined in claim 1, having restoring members for urging the movable members towards their predetermined positions.

3. In control mechanism, a vertical support, a movable member pivotally mounted on said support and adapted to extend outwardly in a predetermined position, a cam member supported by said movable member, and having a locking end face and an outer control face, a second

movable member pivotally mounted on said support and adapted to extend outwardly in a predetermined position, a second cam member supported by said second movable member and having a locking end face and an outer control face, a pivotally mounted control member having spaced followers for engagement with the faces of said cam members, said control member upon movement of one movable member from its predetermined position having one follower positioned by the outer face of one cam member to dispose the other follower in engagement with the locking end face of the other cam member and thereby hold said other movable member against movement from its predetermined position.

4. Control mechanism as defined in claim 3 having resilient restoring members for engagement by said cam members upon movement thereof from their initial positions.

5. In control mechanism, a vertical support, a sleeve pivotally mounted on said support, a movable member carried by said sleeve and adapted to extend outwardly in a predetermined position, a downwardly extending cam block carried by said sleeve and having a locking end face and an outer control face, a second sleeve pivotally mounted on said support, a second movable member carried by said second sleeve and adapted to extend outwardly in a predetermined 30

position, a second cam block carried by said second sleeve and extending upwardly and having a locking end face and an outer control face, a control member pivotally carried by said support and having spaced followers for engagement with the faces of said cam blocks, said control member upon movement of one movable member from its predetermined position having one follower positioned by the outer face of one cam block to dispose the other follower in engagement with the locking end face of the other cam block and thereby hold said other movable member against movement from its predetermined position.

15 6. Control mechanism, as defined in claim 5 having resilient members carried by said support for engagement by said cam blocks upon movement thereof urging said cam blocks towards their initial positions.

20 HARRY J. FERGUSON.
